UNITED STATES PATENT OFFICE.

BURETT H. STEPHENS, OF CHICAGO, ILLINOIS.

REFRIGERATION SYSTEM.

Application filed November 17, 1921. Serial No. 515,747.

To all whom it may concern:

Be it known that I, BURETT H. STEPHENS, a citizen of the United States, and a resident of Chicago, in the county of Cook and State 5 of Illinois, have invented certain new and useful Improvements in Refrigeration Systems, of which the following is a specification.

This invention relates to improvements in 10 systems of refrigeration, and more particularly to the construction of a refrigerating device for cooling air, as, for instance, in cold storage rooms.

The object of the invention is to provide 15 a new and novel construction for refrigerating devices, wherein the cooling process involves the spraying of a suitable cooling liquid into a chamber thru which the air to be cooled is circulated. A further object of the 20 invention is the application of certain improved features calculated to produce more efficient cooling or refrigeration and to overcome the difficulties experienced in present systems of this general character.

The features embodying the invention are 25 set forth in their preferred form in the accompanying drawings, wherein—

Figure 1 is a perspective view of a battery 30 of refrigerating units, one unit being shown with parts broken away to show the complete structure.

Figure 2 is a perspective view of the baffle member mounted in the casing,

Figure 3 is a perspective view of the baffle 35 ring,

Figure 4 is a perspective view of the splash pan, and

Figure 5 is a detail view of a drain pipe, 40 showing the perforations therein.

In illustrating the invention I prefer to show what may be termed a battery of refrigerating units preferably arranged along one side of a storage room and occupying substantially the entire vertical space from 45 the floor to the ceiling, altho, as will hereinafter be pointed out, the entire refrigerating apparatus is designed to be installed in storage rooms of usual height without additional head room for accommodating the apparatus.

In describing the invention, a single unit 50 will be referred to in detail, it being understood that such a unit constitutes a complete refrigerating device, the number of units being multiplied, depending on the size of

the room to be cooled and the proportionate volume of air to be treated.

In general, the refrigerating unit comprises a vertically arranged cylindric housing or casing A open at its upper and lower 60 ends, with sufficient room between the ends and the floor and ceiling of the room to permit a free circulation of air thru the casing.

Surrounding the casing is a wall B, preferably made up of flat vertical wall sections 65 forming a square or rectangular enclosure for the casing and providing a vertical passageway therebetween. As clearly shown in

Fig. 1, wherein the battery of refrigerating units are shown, the outer surrounding walls 70 B consist of parallel front and rear walls

extending thruout the length and end walls extending thruout the width of the units. These outer walls B are preferably con-

structed of suitable insulating composition 75 extending upwardly from the floor level to a point short of the upper extremity of the refrigerating unit or units. The cylindric casing A as well as the outer wall B is sup-

ported upon or suspended from a skeleton 80 frame-work consisting of uprights 1 and laterals 2, preferably consisting of pipe sections and suitable connections at the intersections of the uprights and laterals.

Referring to the casing A, the same comprises an upper casing section 3 and a lower section 4, the upper section being somewhat greater in height and terminating at its lower end at a point substantially midway 85 the height of the complete refrigerating unit or apparatus. Immediately below the upper end of the upper section 3 is provided an enlarged portion 3^a consisting of two conical sections joined together at their bases and tapering in opposite directions. The lower 90 section 4 is a continuation of the upper section, altho separated therefrom by an annular opening formed between the lower end of the upper section and upwardly and out-

wardly flaring end portion 4^a terminating 100 above the lower edge of the upper section 3. The division of the casing into two sections provides an annular opening between the interior of the casing A and the surrounding

space or air passage, and serves a purpose 105 hereinafter to be pointed out. In order,

however, that the annular opening between the adjacent ends of the casing sections 3 and 4 may be controlled as to size or even completely closed, an annular sleeve or band 110

5 surrounds the lower end of the upper section 3, and is adapted to be adjusted vertically by means of suitable adjusting means such as vertical slots 5^a formed in the sleeve 5 and bolts 6 anchored in the casing 3 and extending thru the slots 5^a, said bolts being provided with wing nuts to permit the adjustment to be accomplished by hand. As clearly shown in Figure 1, the sleeve 5 may be lowered until its edge engages the base of the flared portion 4^a of the lower section 4, thereby completely closing the annular opening to the interior of the casing.

As before indicated, the lower end of the casing A terminates a considerable distance above the floor level, and there is located within the lower portion of the lower section 4 and immediately beneath the same the parts of the apparatus utilized for condensing and collecting the cooling liquid which is introduced into the casing at its upper end thru a pipe line 7 terminating in a downwardly directed nozzle 8 located concentrically with respect to the interior 25 of the casing A and just below the opening at the upper end thereof. Altho any suitable type of nozzle may be employed for introducing the cooling liquid into the casing, the use of a nozzle which discharges the liquid laterally in all directions and in the 30 form of a fine spray, is preferred.

Referring now to the condensing and collecting devices just mentioned, the same will be described as follows: Suspended from a spider 9 mounted within the interior of the lower casing section 4 and above the lower end thereof, is a baffle member 10 consisting of a plurality of gable-like sections 10^a radiating from a central point located in the 35 vertical axis of the casing. The several gable-like sections intersect each other to form downwardly and outwardly inclined troughs, whereas the outer vertical edges of each section form inverted V-shaped openings 40 communicating with the open space immediately below. The diameter of the baffle member is less than the internal diameter of the casing section 4, so that an annular passage is formed between the periphery of the baffle member and the inner surface of the casing, permitting the free passage of air thru the inverted V-shaped openings of said baffle member in an inwardly and lateral 45 direction. The baffle member 10 is a sheet metal structure, and, as before suggested, is suspended from the spider 9 and thru the medium of rods 11—11, depending from the spider 9. Formed in the lower portion of the casing section 4 and thruout that portion immediately surrounding the baffle 50 member 10 are rows of openings 12 of a number and size to provide an area in the aggregate substantially equal to the cross-sectional area of said baffle member 10. Surrounding the lower end of the casing

section 4 is an annular baffle plate or skirt 13 terminating a short distance below the lower end of the casing section 4 and extending over and enclosing the openings 12 or what may be termed the perforated section of the casing section 4. The provision of this annular baffle or skirt 13 provides a passageway around the exterior of the casing section 4 which communicates with the interior of the casing thru the openings 12, this passageway opening downwardly so that the air escaping thru said opening into said passage is likewise directly in a downward direction.

Extending circumferentially around the lower edge of the casing section 4 and secured to the inner surface thereof is a baffle ring 14 consisting of a plurality of relatively narrow plates or a strip bent in zig-zag fashion so as to form alternate inverted and upright V-shaped gables conforming generally in arrangement to the gable sections 10^a of the baffle member immediately above. The downwardly projecting portions are further shaped so as to provide outwardly and downwardly inclined troughs. The baffle ring 14 is located immediately below the annular open space surrounding the baffle member 10, and its function will presently be pointed out in detail.

Immediately below the casing section 4 and the lowermost baffle member 14 is a receptacle 15 which may be better termed a splash pan. This splash pan consists of an annular bottom wall 16 and upwardly and outwardly flaring side walls 17 extending above the lower edge of the skirt 13 and outside of the same, its upper marginal portion being preferably bent inwardly, as at 18, so as to abut against the outside of said skirt 13. In the bottom wall 16 of the splash pan is an opening of quite large diameter and substantially equal to the diameter of the uppermost baffle member 10, said opening being surrounded by an upright annular flange 19 forming the inner wall of an annular trough substantially concentric with and in vertical alignment with the zig-zag baffle ring immediately above. Communicating with the splash pan 15, and, as a matter of fact, with the annular trough formed at the bottom thereof, is a series of drain pipes 20 arranged in spaced relation around said trough. These pipes 20 extend downwardly into an open trough 21 supported just above the floor level on short transverse beams 22, which also serve as a support for the skeleton frame on which the entire apparatus is mounted or suspended.

The pipes 20 are preferably perforated by making triangular shaped cuts in the pipe and then bending the pointed portions of metal inwardly, as is clearly shown in detail in Figure 5, these cuts being formed so

that the inwardly bent portions extend upwardly and inwardly into the interior of the pipe with the result that the liquid flowing downwardly thru the pipes will escape to the outside surface and continue downwardly in contact therewith. In other words, a part of the liquid will be conducted thru the pipe and a portion conducted on the outer surface of the pipe, the purpose of this treatment, as will hereinafter be pointed out, being to provide additional cooling surface, and thence added refrigeration.

As hereinbefore explained, Figure 1 illustrates a typical installation and with the following explanation it will be seen that the entire apparatus may be readily installed and easily assembled without making elaborate preparations or especially constructed space to receive a battery of the refrigerating units. The skeleton frame may be readily assembled and supported upon the transverse beams 22 which rest upon the floor of the storage room, the casing sections 3 and 4 being suspended within the skeleton frame and the sections of the wall B mounted upon or suspended on the outside of the frame. As clearly shown in Figure 1, the suspension of the parts upon the skeleton frame is accomplished by the use of straps 23 which are riveted to the several parts and are bent at their free ends in the form of hooks which engage the laterals 2 of the skeleton frame. The use of these straps 23 applies to both sections of the casing 3 and 4 as well as the splash pan 15. A similar method of mounting the walls B may also be employed, the result being that the entire apparatus is portable and readily installed in any storage room or area without necessitating any alteration other than that necessary to pipe the cooling liquid along the ceiling to the several refrigerating units.

The continuous cooling process or refrigeration of the air depends upon the application of a well known principle; namely, that the colder air sinks to the lowest level and therefore the warmer air of the room rises and enters the upper end of the refrigerating unit, where it immediately comes in contact with the cooling liquid, and its temperature lowered. Hence it will sink to the lower end of the unit and ultimately be discharged into the room at a low level. Thus a cycle of alternate cooling and heating processes are set up, with the result that a constant circulation is promoted thru the apparatus and the space to be cooled. So in this instance, the warmer air rising to the ceiling enters the refrigerating unit thru the opening at the upper end of the casing 3 and immediately comes in contact with the cooling liquid, which is preferably brine cooled to a temperature somewhat below normal temperature of the room and which is sprayed into the casing thru the nozzle 8. As before

suggested, the nozzle produces a very fine spray which is discharged in a laterally as well as a downward direction; a portion striking the wall of the casing thruout the enlarged portion 3a is condensed and flows down the inner surface of the casing in liquid form, thereby maintaining the walls of the casing at a very low temperature. The remaining portion of the spray discharged downwardly into the casing intermingles with the air and absorbs the heat therefrom. Thus the cooling process is of a two-fold nature; namely, by the intermingling of the spray in the air, and by direct contact with the liquid-coated surface of the casing. As the air travels downwardly to the lower end of the casing, a portion of the brine or the spray becomes condensed, assuming the form of comparatively large globules of liquid which become readily separated from the air as it passes inwardly beneath the gable sections of the baffle member 10 or outwardly thru the openings 12 in the casing section 4. A considerable portion, however, of the brine remains in suspension in the form of a fine mist which is not so readily separated from the air. It is therefore the complete removal of the residual spray or moisture from the air that demands the use of the arrangement of baffles such as here shown and described. The air now comes in contact with the baffle member 10 which serves to condense the spray and further alter the direction of the air so as to allow the condensed liquid to be freed, whereas the air travels in a lateral direction either inwardly thru the vertical V-shaped openings of the baffle member 10 or outwardly thru the openings 12, and thence downwardly again into the splash pan 15. It may be explained at this point that the provision of the openings 12 and the surrounding baffle or skirt 13 is to equalize the pressure at the lower end of the casing and to minimize the retarding effect of counter currents which would be set up due to the restriction caused by the baffle member 10, with the result that the air may pass freely in either lateral direction from the lower end of the casing. The ultimate outlet for the air is the large opening in the bottom of the splash pan 15 from whence it is discharged downwardly and thence laterally toward a discharge opening in the wall B, preferably having the form of a series of downwardly inclined louvres 24 located just above the floor level. These louvres form a section of the outer wall B facing outwardly toward the room or space to be cooled. It is to be observed that the air in passing from the lower end of the casing and thru the large annular opening in the bottom wall of the splash pan 15 circulates thru and around the pipes 20 extending downwardly into the open tank or trough 21. In this manner

additional cooling effect is secured, such effect being increased by the passage of the brine downwardly on the outside of these pipes. In this way the utmost cooling effect is secured from the brine, and hence the efficiency of the system promoted.

As before suggested, a portion of the cooling liquid or brine introduced into the casing condenses on the inner surface thereof and passes downwardly in the form of a liquid until it ultimately reaches the lower edge of the lower casing 4. Thence it is collected by the lower baffle ring 14 flowing toward the several narrow troughs formed at the several apexes and from thence discharged outwardly into the splash pan. From the splash pan or trough thereof, the cooling liquid thus accumulated flows into the open tank 21 thru the pipes 20 as already described, the liquid finding its way back to the source of supply.

The description of the operation of the apparatus has thus far been confined to the interior of the casing A and the cooling of the air that passes therethru. However, an additional or auxiliary cooling process is carried on simultaneously in the vertical space between the casing and the outer or surrounding walls B. In addition to the circulation of air thru the interior of the casing A there is also set up a corresponding circulation in a downwardly direction thru the passage surrounding the exterior of the casing, the cooling process being carried out by the contact of the air with the outer surface of the casing, the same being maintained at a low temperature by the presence of the cooling liquid within the interior of the casing and particularly by the liquid which flows down the inner surface thereof. In order to insure the circulation in the surrounding passage, a syphon action is introduced thru the medium of an annular opening between the ends of the upper and lower casing sections 3 and 4, as heretofore described. This action will be understood from the following: The downward circulation of the air thru the interior of the casing will manifestly draw a portion of the air from the surrounding passage into the interior and thru the annular opening just referred to, thereby producing a suction sufficient to promote a downward circulation in the surrounding passage. The larger portion of the air thus handled continues downwardly beyond the opening and is discharged outwardly into the room thru openings formed between the three uppermost louvres 24^a, Figure 1, these openings being identified by and separated from the remaining louvre openings by a baffle or partition plate 25 extending from the casing outwardly to the louvres and forms the bottom wall of the surrounding passage, and also separates the same from the space immediately

below forming the outlet passage for the air discharged from the interior of the casing. It is to be noted that the baffle plate 25 has an outwardly and downwardly inclined portion immediately adjacent the louvres 24^a, thus serving to promote the flow of the air outwardly thru the openings. Furthermore, the baffle plate 25 acts as a partition separating the stream of cold air discharged from the interior of the casing from the stream of air passing downwardly thru the surrounding passage, it being manifest that otherwise portions of the cold air would endeavor to pass upwardly thru the outer passage and oppose the current of air passing therethru in a downward direction.

From the preceding description it will be seen that a single refrigerating unit utilizes the interior of the casing A as well as the external surface thereof as a cooling surface, in addition to the cooling effect that results from the intermingling of the air and the spray. It follows, therefore, that increased volume of air may be cooled by a single unit and the efficiency materially increased. Attention has already been called to the method of controlling the syphon action whereby the circulation of air thru the outer passage may be regulated.

One of the problems in providing a practical refrigerating system in which the cooling is effected by the intermingling of the air and cooling liquid in the form of a spray, has been alluded to; namely, to completely eliminate or remove the moisture from the air at the completion of or during the cooling process. In the apparatus herein described, the complete separation is accomplished by the particular arrangement of baffle members which provides, by reason of its conformation, ample area for the condensation of the spray into its liquid form, and the breaking up of the air current in such a way that it may free itself of moisture before it is ultimately discharged into the room. This is clearly seen from the fact that the air in escaping from the casing must pass inwardly beneath the gable-like structure of the baffle member 10 and thence downwardly thru the large opening in the splash pan, or else outwardly thru the openings 12 into contact with the skirt 13, and thence downwardly thru said large outlet opening, in either event the air having ample opportunity of eliminating all moisture. By the arrangement of the inclined troughs provided by the upper and lower baffle members, the uppermost troughs drain to the lower troughs, which in turn drain into the splash pan, so that all of the liquid is ultimately collected in the splash pan and returned to its source of supply. The added cooling effect of the drain pipes 20 has already been referred to.

Having described the invention, and a

preferred construction embodying the same, I claim:

1. In a refrigerating system, the combination of a vertical open-ended casing through which the air to be cooled is circulated, means for spraying a cooling liquid into the upper end of said casing, an annular baffle member comprising a plurality of gable sections mounted in the lower end portion of said casing and having its periphery spaced from the inner surface thereof, an intermediate baffle member circling the inner surface of the casing below the periphery of said annular baffle member, and a receptacle at the lower end of said casing. 70
2. In a refrigerating system, the combination of a casing open at its end, and through which the air to be cooled is circulated, means for spraying a cooling liquid into the upper end of said casing, an annular baffle suspended within the lower end portion of said casing and having its periphery spaced from the surface thereof, an intermediate baffle member circling the wall of said casing below the annular baffle member, and comprising V-shaped baffle sections directed inwardly, and a receptacle below the lower end of said casing. 85
3. In a refrigerating system, the combination of a vertical casing open at its ends, means for spraying a cooling liquid into the upper end of said casing, an annular baffle suspended within the lower portion of said casing and spaced at its periphery from the surface thereof, the casing being perforated adjacent said baffle member, an annular baffle ring extending around the inner surface of said casing below said annular baffle member and said perforated portion, and a receptacle enclosing the lower end of said casing including the perforated portion thereof. 95
4. In a refrigerating system, the combination of a vertical casing open at its ends, means for spraying a cooling liquid into the upper end thereof, a baffle member mounted centrally within the lower portion of said casing and comprising radially extending gable-like sections, a similarly formed baffle ring circling the surface of the casing below said baffle member, and a splash pan mounted beneath said casing. 100
5. In a refrigerating system, the combination of a vertical casing open at its ends, means for spraying a cooling liquid into the upper end thereof, a baffle member mounted in the lower portion of said casing comprising radially disposed gable-like sections and intermediate troughs, the periphery of said baffle member being spaced from the wall of the casing, and perforations formed in said wall portion surrounding said baffle member, and a splash pan beneath said casing and provided with annular walls enclosing the perforated lower 115
- end portion of said casing, and an air discharge opening in its bottom wall surrounded by an upright flange forming with said side wall an annular trough, and a series of drain pipes depending from said trough. 125
6. In a refrigerating system, the combination of a vertical casing open at its ends, means for spraying a cooling liquid into the upper end thereof, a baffle member mounted in the lower portion of said casing comprising radially disposed gable-like sections and intermediate troughs, a baffle ring secured to the lower edge of said casing and comprising a plurality of V-shaped troughs directed inwardly, a splash pan mounted beneath said casing provided with a flanged air opening in the center of the bottom wall thereof and forming an annular surrounding trough into which the liquid from said baffle ring drains, and a drain pipe communicating with said splash pan. 130
7. In a refrigerating system, the combination of a vertical casing open at its ends, means for spraying a cooling liquid into the upper end thereof, a baffle member mounted in the lower portion of said casing, a splash pan beneath said casing provided with an air discharge opening thru its bottom wall, a series of vertical drain pipes surrounding said opening, said pipes being perforated to permit the liquid to flow downwardly on the outer surface thereof. 135
8. In a refrigerating unit, the combination of a vertical casing open at its ends, means for spraying a cooling liquid into the upper end thereof, a receptacle at the lower end of said casing, a plurality of drain pipes communicating with said receptacle, said pipes being perforated to permit the liquid to flow on the outer surface thereof, and an open tank into which said drain pipes empty. 140
9. In a refrigerating unit, the combination of a vertical casing open at its ends, means for spraying a cooling liquid into the upper end thereof, a receptacle below said casing into which the liquid is collected, a plurality of drain pipes communicating with said receptacle and depending into a tank below said receptacle, said pipes being located in the path of the cooled air, and perforated thruout their length to permit the flow of the liquid down their outer surfaces. 145
10. In a refrigerating system, the combination of a vertical casing open at its ends, means for spraying a cooling liquid downwardly into said casing, a vertical wall surrounding said casing and forming an air passage therebetween, and having a discharge opening in the lower portion thereof and an opening in said casing intermediate its ends communicating with said passage. 150

11. In a refrigerating system, the combination of a vertical casing open at its ends and having an opening intermediate its ends, means for spraying a cooling liquid at the upper end of said casing, a vertical wall surrounding said casing forming an air passage and having an opening therein at its lower portion forming a discharge for the air delivered from the lower end of said casing and circulated downwardly through said passage.

12. In a refrigerating system, the combination of a vertical casing, a wall surrounding said casing, thereby forming inner and outer air passages discharging at their lower ends, means for spraying cooling liquid downwardly into the upper end of said casing, means for promoting condensation of the liquid at the lower end of said casing, means for discharging the air from said casing, and an opening in said outer wall forming a common air discharge into the space to be cooled.

13. In a refrigerating system, the combination of a vertical casing open at its ends, means for spraying a cooling liquid at the upper end of said casing, a wall surrounding said casing and extending substantially throughout the height thereof, said wall being spaced from said casing to form an exterior air passage for the circulation of air in contact with the exterior of said casing, means in said casing for promoting the condensation of the liquid, and a common discharge opening in said wall for the air discharged from the lower end of said casing and circulated through said outer passage.

14. In a refrigerating system, the combination of a vertical casing open at its ends, means for spraying cooling liquid into the upper end thereof, means for condensing the cooling liquid at its lower end, comprising a receptacle, a trough, and a plurality of drain pipes extending from said receptacle to said trough, and a vertical wall surrounding said casing, receptacle, pipes, and trough and having a louvred opening in the lower portion thereof.

15. In a refrigerating system, the combination of a vertical casing open at its ends, a wall surrounding said casing and forming an outer air passage therebetween, said casing having an annular opening intermediate its ends communicating with said passage, means for spraying a cooling liquid into said casing, means for promoting the condensation of the liquid adjacent the lower end of said housing, and a common discharge opening formed in the lower portion of said surrounding wall.

16. In a refrigerating system, the combination of a vertical casing open at its ends, means for spraying a cooling liquid in said

casing, a wall surrounding said casing and providing an outer vertical air passage, said casing being divided intermediate its ends into sections spaced apart vertically to form an annular opening communicating with the surrounding passage, and means for regulating the size of said opening.

17. In a refrigerating system, the combination of a vertical casing open at its ends, means for spraying a cooling liquid into the upper end of said casing, a vertical wall enclosing said casing and forming an auxiliary air passage, said casing being divided substantially midway its height into sections, spaced apart vertically to form an annular opening communicating with the surrounding passage, and a sleeve mounted at the end of one of said sections and adapted to be adjusted to open and close said opening.

18. In a refrigerating system, the combination of a vertical casing including a plurality of sections spaced apart at their ends, the lower of said sections having a flaring end portion extending outwardly and beyond the end of the adjacent section, means for spraying cooling liquid into the top of said casing, and means at the bottom of said casing for promoting the condensation of said liquid.

19. In a refrigerating system, the combination of a casing open at its end and erected in vertical position, said casing consisting of sections spaced apart at their adjacent ends to provide an annular opening, the lower of said sections having a flaring end portion enclosing the end of the adjacent section, and means for regulating the size of said opening.

20. In a refrigerating system, the combination of a vertical casing open at its ends, means for spraying said liquid downwardly into said casing, a wall enclosing said casing and forming an outer air passage, an opening in the lower portion of said outer wall, and a partition plate extending from said casing above the lower end thereof, and intersecting said opening between its upper and lower edges, thereby forming separate discharges for the air delivered from the casing and from the outer passage.

21. In a refrigerating system, the combination of a vertical casing, a wall surrounding said casing forming inner and outer passages, means within said casing for spraying cooling liquid downwardly therein whereby a downward circulation of air is promoted through said casing, a vertically disposed discharge opening formed in the lower portion of said wall, louvres mounted in said opening, and a horizontal partition wall dividing said opening vertically and extending to said casing, the upper portion of said opening forming the

discharge for said outer passage, and the lower portion forming the discharge for the air from said casing.

22. In a refrigerating system, the combination of a vertical casing open at its ends, a wall substantially enclosing said casing and forming a passage therebetween, said casing comprising upper and lower sections spaced apart vertically forming an annular opening communicating with said outer passage, means for spraying a cooling liquid into said casing, means for condensing the liquid adjacent the lower end of said casing, an opening in the lower portion of said wall, and a partition plate above the lower end of said casing for preventing the upward circulation of air through said outer passage.

23. In a refrigerating unit, the combination of a casing adapted to be suspended above the floor of a space to be cooled, a frame structure consisting of uprights and

laterals erected upon said floor, said casing being provided with hooked members engaging said laterals of said frame, and wall sections suspended from and applied to the exterior of said frame, and substantially enclosing said casing.

24. In a refrigerating unit, the combination of a casing adapted to be erected in vertical position above the floor of the space to be cooled, and consisting of separate tubular sections, a frame structure consisting of uprights and lateral members resting upon said floor, said sections being provided with hooked supporting arms adapted to engage said frame whereby said sections hang therein, and outer wall sections removably suspended from said frame and enclosing the same and said casing. 40

In witness whereof, I hereunto subscribe my name this 14th day of November, A. D., 1921.

BURETT H. STEPHENS.
